UNITED STATES PATENT OFFICE.

JAMES W. GAULT AND WILLIAM A. FORMAN, OF MURPHYSVILLE, KY.

TOBACCO-ELEVATOR.

SPECIFICATION forming part of Letters Patent No. 224,172, dated February 3, 1880.

Application filed December 5, 1879.

To all whom it may concern:

Be it known that we, JAMES W. GAULT and WILLIAM A. FORMAN, of Murphysville, in the county of Mason and State of Kentucky, have 5 invented a new and Improved Tobacco-Elevator, of which the following is a specification.

Figure 1 is a front elevation of the elevator, showing the position of the carrying-arms when elevating or lowering the tobacco. Fig. 2 is a 10 side elevation of the same. Fig. 3 is a front elevation, showing the position of the carrying-arms when depositing the tobacco-sticks upon or removing them from the rails.

Similar letters of reference indicate corresponding parts.

The object of this invention is to provide an improved elevator for hoisting tobacco plants and leaves and suspending them upon the rails in drying or curing barns.

20 In the drawings, A represents the standard, having pivoted upon it near its head a cross-bar, B. C is a slide capable of vertical movement, held to the standard A by the clamps or loops *a*, and fastened on the face of this slide 25 is a plate, D, with an upper corner cut off at an angle of about forty-five degrees, as shown at *b*. Pivoted just above this plate D, on the face of the slide C, is an arm, E, provided with a hook, *c*, at either end. For purposes hereinafter set forth, another arm, F, is sometimes 30 pivoted to the face of the slide C a little below the plate D, said arm F being provided with a projecting rod or hook, *d*, at either end, as shown, and being also connected at each 35 end with the ends of the arm E by the parallel connecting-pieces G, which are loosely pivoted to the said arms E F.

Secured to the top of the standard A is a 40 sheave, H, over which passes a rope, I, one end of which is secured to the slide C, while the other end is secured to that end of either arm E F which is farthest from the sloping corner *b* of the plate D, the bight of the said 45 rope I hanging within reach of the operator on the floor of the curing building or barn.

In the tobacco-curing barns the rails K, for supporting the tobacco-sticks L, are set in several tiers or rows above each other, and about three and a half feet apart laterally. The tobacco-sticks L should then be about four feet

long and the arms E F about three feet long. This apparatus is sufficiently light to be easily moved about, and is used by suspending it by the cross-bar B, so that the ends of the said cross-bar will rest across and upon the two upper rails K, as shown; then a tobacco-stick, L, having the tobacco leaves or plants suspended on it, is laid across the hooks *c*, as shown. By pulling upon the rope I the arm E is then elevated, inclined at such an angle that it will readily pass between the rails K so far that the lower end of the said stick L will be raised above the rail K on which it is to rest; then a pull upon that part of the rope I which is made fast to the arm E in this case brings 65 said arm E to a horizontal position, when it is lowered so that the stick L, carrying the tobacco, will rest across the rails K. The arm E is then lowered to receive another stick, L, which, being elevated, is in like manner deposited with its load on the next lower tier or row of rails, and so on until one stick has been deposited on each tier or row of rails; then the elevator is moved the distance it is desired to hang the sticks apart, and the operation proceeded with, always hanging the sticks from 70 the top to the bottom of the building.

To take the tobacco down, the rope I is made fast to the opposite end of the arm E, which is then elevated until the hooks *c* engage under 75 the stick L and lift it far enough above the rails K to disengage it therefrom and incline it at such an angle that it can pass down laterally between the said rails K.

When the tobacco is very heavy or green, 80 the arm F is connected to the arm E, and parallel to it, as shown, so that the hooks or rods *d* shall hold the tails of the tobacco-leaves in 85 position that they may not interfere with the elevating or depositing process.

This device can easily be worked by one person, and by it the tobacco-sticks can easily be hung six inches apart, or closer, if desirable, thus economizing all the hanging-room in a curing-barn; and in this respect our elevator 90 possesses a great advantage over those old-style elevators whose carrying-arm, analogous to our arm E, is hoisted in a diagonal position and then swung into position for depositing the tobacco-stick by a rotary motion. These 95 100

old-style elevators cannot place the tobacco-sticks on the rails much less than two feet apart, and must leave a space of about two feet at the beginning and about four feet at the 5 ending of each rail.

Having thus described our invention, we claim as new and desire to secure by Letters Patent—

The arm F, provided with hooks or rods d,

in combination with the arm E, substantially 10 as herein shown and described, for holding the tails of tobacco-leaves in position when being elevated and deposited by an elevator.

JAMES WASHINGTON GAULT.
WILLIAM ANDREW FORMAN.
